UNITED STATES PATENT OFFICE.

AUGUST SILK AND PETER LIGHT, OF CINCINNATI, OHIO.

STEAM-TRAP.

SPECIFICATION forming part of Letters Patent No. 712,441, dated October 28, 1902.

Application filed May 12, 1902. Serial No. 106,859. (No model.)

To all whom it may concern:

Be it known that we, AUGUST SILK and PETER LIGHT, citizens of the United States, and residents of the city of Cincinnati, in the county of Hamilton and State of Ohio, have invented certain new and useful Improvements in Steam-Traps; and we do declare the following to be a clear, full, and exact description thereof, attention being called to the accompanying drawings, with the reference-numerals marked thereon, which form also a part of this specification.

This invention relates to certain improvements in details of construction of steam-straps, as more fully set forth hereinafter.

In the following specification, and particularly pointed out in the claims at the end thereof, is found a full description of the invention, together with its operation, parts, and construction, which latter is also illustrated in the accompanying drawings, in which—

Figure 1 is a side view of our trap complete. Fig. 2 is a longitudinal section of the same. Fig. 3 is a top view with the inlet-opening open and parts broken away. Fig. 4 is a vertical cross-section on line 4 4 of Fig. 2. Fig. 5 is a similar section on line 5 5 of Fig. 2. Fig. 6 is an enlarged sectional detail view shows the outlet-valve, its seat, and the attachment-nipple which supports this latter.

9 is a housing of suitable shape and size, which may be supported in any convenient manner—as, for instance, it may rest on legs 10. It has an inlet-opening 11 to permit access for placing the operating parts and for any other purposes, which opening is normally closed by a cap 12. In its upper part it is provided with a steam-inlet 13 and in its lower part with an outlet 14 to permit exit of the accumulating condensation. This outlet is controlled by a valve 15, supported so as to be capable of moving in a vertical direction to or from its seat 16. This valve-seat is formed in a separate piece, (see Fig. 6,) which is independently removable for repair or renewal, and rests within a nipple 17, which serves at the same time as a means for connecting the outlet-pipe 18. This nipple is held in position by means of a union coupling 19 to a plug 21, which screws in the outlet-opening 14 of the housing. For its movement valve 15 is connected to the lower end of a rod 22, preferably removable, the upper

end of which connects to the free end of one of the branches of an angle-lever 24. At its pivot it is laterally extended, forming trunnion-journals 25, one on each side, the outer ends of which are pivotally supported between the forked branches 26 of a post 27. This latter is attached to the bottom of the housing. To the free end of the other branch of the angle-lever there connects an arm 29, which on its free end carries a float 31. It will now be understood that as soon as the accumulated condensation lifts the float the outlet-valve follows and permits exit of part of the accumulation until this latter recedes to its normal level, when said valve closes again. The action of the valve is very prompt and quite sensitive to the actions of the float, to the movements of which it responds freely, since the center on which its supporting-arm swings is coincident with the fulcrum of the angle-lever. The movement of the valve is not extensive, and the same readily guides itself to and from its seat; but, if necessary, suitable means for guiding it may be provided—like, for instance, the customary lateral wings commonly used on valves. The inlet-opening is provided with a pipe 33.

Steam-traps accumulate usually more or less sediment, which requires removal from time to time. We use the normal outlet-valve to do this, and accordingly provide means whereby this valve may be raised and held open independently of the float. For such purpose we provide a rod 34, disposed transversely below the float-arm 29 and supported in the side of the housing. It is provided with a projection in the shape of an eccentrically-mounted cam 35, which is so attached as to be below float-arm 29, so that when rod 34 is rotated it is capable of raising said arm. For its manipulation one end at least of this rod projects to the outside of the housing, where it is provided with a handle 36. Normally it is so turned that this projection 35 does not come in contact with arm 29 when the float is in its lowest position, so as not to interfere with the closing of the outlet-valve. The extreme positions of this cam when inactive or when used to open the valve may be indicated on the outside of the housing by means of stops 37, operating in conjunction with handle 36 and limiting the movement of the same. As a matter of con-

venience and to suit positions of the trap and possibilities of access thereto we permit both ends of rod 24 to project, so that handle 36 may be attached on either side of the trap. 5 At its end where this rod passes through the sides of the housing it is necessary to provide stuffing-boxes 38. In view of the fact that we use this outlet-valve also as a blow-off valve, we favor the accumulation of sediment 10 near it and its movement toward it by providing a pocket 39, in the deepest part of which the outlet is located. 41 is a conventional glass gage to show the level of accumulation. It will be noted that the moving parts 15 of this valve are reduced to a minimum, thus reducing friction and wear, all of which results in a device reliable and effective in operation and quickly affected by any variations in the level of the accumulation. While 20 all parts are inclosed, they are also readily accessible for inspection and repair or renewal, and parts most subject to wear, like valve 15 or its seat, may be had access to and renewed from the outside by simply removing coupling 19.

Having described our invention, we claim as new—

1. In a steam-trap, the combination of a closed housing, a steam-inlet in the upper part 30 thereof, an outlet-opening in the lower part, a screw-plug 21 fitted from below into this outlet-opening and projecting with its lower end below the outside of the trap, a pipe-attaching nipple 17, a union coupling 19 whereby the same is removably attached to the lower free end of the screw-plug, a valve-seat member 16 fitted detachably between the upper end of nipple 17 and the lower end of plug 21, a valve fitted to this seat so as to control 35 the outlet-opening, a swinging float-arm thereon and operative connection between it and the outlet-valve mentioned whereby the same is automatically actuated by the movements of the float.

45 2. In a steam-trap, the combination of a box-shaped housing, an access-opening in its top, a cap to close this opening a steam-inlet, an outlet-opening for the condensation, a valve controlling the same, a pipe-attaching 50 nipple 17, an independent valve-seat member 16, a plug 21 fitted into the outlet-opening, a coupling whereby this nipple is detachably connected in position below the outlet-opening, a valve 15 fitted to valve-seat 16, a rod 22 to the lower end of which valve 15 is connected, an angle-lever 24 to one of the free 55 ends of which the upper end of this rod is attached, a post 27 having branches 26 between which the angle-lever is pivotally supported, said post being immediately below the access-opening in the top of the trap, an arm 29 connected to the other end of the angle-lever, a float at the free end of this arm to automatically 60 actuate the angle-lever and means 65 accessible from the outside to positively raise this arm.

3. In a steam-trap, the combination of a

box-shaped housing, an access-opening in its top, a cap to close this opening, a steam-inlet, a pocket 39 formed by a depression in its 70 otherwise flat bottom, an outlet-opening in the deepest part of this pocket, a pipe-attaching nipple 17, an independent valve-seat member 16, a plug 21 fitted into the outlet-opening, a coupling whereby this nipple is 75 detachably connected in position below the outlet-opening, a valve 15 fitted to valve-seat 16, a rod 22, to the lower end of which valve 15 is connected, an angle-lever 24 to one of the free ends of which the upper end of this 80 rod is attached and which is laterally enlarged to form trunnions 25 on both sides, a post 27 having branches 26 between which the angle-lever is pivotally supported, said post being immediately below the access-opening 85 in the top of the trap, an arm 29 connected to the other end of the angle-lever, a float at the free end of this arm to automatically actuate the angle-lever and means accessible from the outside to positively raise this arm. 90

4. In a steam-strap, the combination of a closed housing, a steam-inlet in the upper part thereof, a pocket in the otherwise flat bottom, an outlet-opening in the lowest part of this pocket, a screw-plug 21 fitted from below into this outlet-opening and projecting with its lower end below the outside of the trap, a pipe-attaching nipple 17, a union coupling 19 whereby the same is removably attached to the lower free end of the screw-plug, a valve-seat member 16 fitted detachably between the upper end of nipple 17 and the lower end of plug 21, a valve fitted to this seat so as to control the outlet-opening, a swinging float-arm thereon and operative connection between it and the outlet-valve mentioned whereby the same is automatically actuated by the movements of the float. 95 100 105

5. In a steam-trap, the combination of a closed housing, a steam-inlet in the upper 110 part thereof, an outlet-opening in the lower part, a screw-plug 21 fitted from below into this outlet-opening and projecting with its lower end below the outside of the trap, a pipe-attaching nipple 17, a union coupling 19 115 whereby the same is removably attached to the lower free end of the screw-plug, a valve-seat member 16 fitted detachably between the upper end of nipple 17 and the lower end of plug 21, a valve fitted to this seat so as to 120 control the outlet-opening, a swinging float-arm thereon, operative connection between it and the outlet-valve mentioned whereby the same is automatically actuated by the movements of the float and means accessible 125 from the outside whereby this float-arm may be positively actuated by manual operation.

In testimony whereof we hereunto set our signatures in the presence of two witnesses.

AUGUST SILK.
PETER LIGHT.
